(57) **CLAIM**

The ornamental design for the dental handpiece, as shown and described.

DESCRIPTION

FIG. 1 is a bottom perspective view of a dental handpiece in accordance with my new invention;

FIG. 2 is a top perspective view thereof;

FIG. 3 is front elevation view thereof;

FIG. 4 is a bottom plan view thereof;

FIG. 5 is a left side elevation view thereof;

FIG. 6 is a right side elevation view thereof;

FIG. 7 is a top plan view thereof; and,

FIG. 8 is a rear elevation view thereof.

The broken lines shown in the figures represent portions of the dental handpiece and form no part of the claimed design.
